UNITED STATES PATENT OFFICE

WILLIAM W. MACFARLANE, OF ELKINS PARK, PENNSYLVANIA, ASSIGNOR, BY MESNE ASSIGNMENTS, TO THE UNION SWITCH & SIGNAL COMPANY, OF SWISSVALE, PENNSYLVANIA, A CORPORATION OF PENNSYLVANIA

TRAIN-CARRIED CIRCUIT SYSTEM

Application filed September 20, 1917, Serial No. 389,187. Renewed June 15, 1920.

The present invention relates generally to a train carried system of train control of the character disclosed in applications Ser. No. 82,861, filed Mar. 8, 1916, and Ser. No. 95,305, filed May 4, 1916, this application being a continuation in part of the subject matter thereof.

The main object of this invention is to produce a system having speed control elements of widely diverse character to control a train under entirely different traffic conditions.

One feature of the invention resides in the employment of two speed control means, one of which completes a circuit through an electroresponsive device to hold the train control means inoperative while the train is running below a certain speed; and another one of which completes a circuit through said electroresponsive means while the train is running below a certain lesser speed together with means for rupturing the connection through the first mentioned speed control means under certain traffic conditions. Thus, the first mentioned speed control means may maintain the integrity of the circuit while the train is running at an intermediate speed suitable for caution conditions; and the other speed control means will maintain the integrity of a similar circuit while the train is running below a certain minimum speed, say from four to ten miles per hour, suitable for danger conditions. When, therefore, the circuit maintained through the first speed control means is ruptured by the automatic devices acting under certain traffic conditions, it is evident that the speed of the train will be cut down to a pre-determined minimum.

In addition to the foregoing, means are also provided for establishing a circuit independent of the speed control means through said electroresponsive means when the train is in a safe zone. Furthermore, in addition to all the foregoing, there may be an additional circuit having a speed control device that will limit the maximum speed at which the train can run under safety conditions.

The train controlling means may, of course, assume any desired form but are here conveniently illustrated by a train pipe and

valves and means for venting the same; and the electroresponsive devices may likewise be of any suitable construction but as here shown take the form of two magnets controlling two valves in the train line and which may act independently to "bleed" the train line. Similary, the speed control means may be of any desired character and two of said means may be combined in one structure consisting, preferably, of a plurality of contacts immersed in a mercury container.

Other features will appear as the specification proceeds.

In the drawing:

Figure 1 is a diagrammatic view of an embodiment of the invention showing a train controlling system of cab circuits including speed controlled and timing mechanism automatically responsive to conditions of safety and danger.

Figure 2 is a diagrammatic view of an embodiment of the invention in which the train controlling apparatus is responsive to conditions of safety, caution and danger.

In Figure 1 of the drawing there is illustrated a preferred embodiment of the invention in which a train-carried translating device 1 is arranged to have continuous electrical communication with the respective track rails 2 and 3 through contact shoes 4 and 5 to which the terminals of the translating device are connected by means of conductors 6 and 7. The partial circuit thus formed, through which current may flow from rail to rail, is constructed to offer a very low resistance to the passage of current therethrough, so that the proportionate volume of current diverted from the paths formed by the wheels and axles is sufficient to operate the translating device or relay 1. The coil of relay 1 preferably consists of a helical strip of copper, or other highly conductive material, having a comparatively large cross sectional area. The conductors 6 and 7 are preferably copper cables that lead to and are embedded in contact shoes 34 and 35.

The armature 8 of relay 1 is adapted to be held in engagement with contact plate 9 in the normally energized condition of the relay. A stop 10 is provided against which the ar-

ture is biased by gravity when current is not flowing through the relay. Contact plate 9 is engaged by armature 8 to close the main control circuit which includes battery 11, conductor 12, conductor 13, armature 8, contact plate 9, conductor 14, relay 15, and conductor 16, back to battery. Relay 15 is thus energized to hold members 17 and 18 of its double armature against front contacts 19 and 20 thereby closing the circuits through the green, or safety, lamp 21 and also through the brake controlling magnet 22.

The circuit through safety lamp 21 includes battery 11, conductor 12, conductor 13, conductor 23, armature 17 of relay 15, front contact 19, conductor 24, safety lamp 21, conductor 25, and conductor 16 back to battery. Current to energize the brake magnet 22 flows over a shunt circuit from conductor 23, to armature 18, front contact 20, conductor 26, conductor 27, magnet 22, conductor 28, and conductor 16.

Upon deenergization of control relay 1 due to danger conditions, armature 8 will break contact with contact plate 9 whereupon relay 15 will drop its double armature to break the circuits through safety lamp 21 at the front contact 19 and through the brake magnet at the front contact 20. Deenergization of magnet 22 will set the brake operating mechanism into action. Simultaneously with this, the red, or danger, lamp 29 will be lighted and bell 30 actuated by means of current supplied from battery 11, conductor 12, conductor 13, conductor 23, armature 18, back contact 31, conductor 32, conductor 33, lamp 29, conductor 34 to common return conductor 16, and also from conductor 33, to bell 30, conductor 34^a, and conductor 34 to common return conductor 16 back to battery. Thus, upon the entrance of a train into a danger zone, danger signals will be actuated in the cab and a brake actuating mechanism will be set into operation.

Brake magnet 22, to which reference has been made, is adapted to control a valve operating mechanism through the connection of the plunger core 35 with lever 36 pivoted to a stationary support at 37. Valve stem 38, carrying valves 39 and 40, is adapted to be held in an elevated position by lever 36 when magnet 22 is energized. Valve 39 operates with a valve seat 41 to control the flow of air from the train pipe 42 through pipe 43 to cylinder 44. A piston 45 in cylinder 44 is connected through piston rod 43 with the stem 47 of brake valve 48 adapted to control an exhaust port in the train pipe 42.

In order to retard, to some extent, the action of the automatic brake actuating mechanism to give the engineer time to slow down his train through the manual control, as well as to allow the train to pass over a dead section at a cross-over, or the like, regulating chamber 49 is provided.

This regulating chamber consists of a cylinder 50 in which is mounted a piston 51. The cylinder 50 is in constant communication with valve chamber 52 and cylinder 44 through passage 53.

The regulating, or timing, cylinder 50 is preferably of such size that an appreciable interval of time will be required to supply sufficient air thereto through the comparatively small pipe 48 to raise the pressure in chamber 49 and cylinder 44 to a point necessary for operation of piston 45.

In order to prevent the complete exhaustion of pressure from the train pipe following an action of the automatic brake controlling mechanism, a spring 55 is mounted on valve stem 46 and bears against a collar 57 thereon to move the piston to inoperative position when the pressure in the brake pipe and chamber 49 is lowered to a certain predetermined minimum. The degree of pressure exerted by spring 55 may be varied by adjusting the position of the slidable abutment member 58.

Provision is made by means of the speed controlled device 59 for allowing a movement of the train under greatly reduced speed when danger conditions exist so that, for example, a train might creep forward into a block occupied by a disabled train for the purpose of giving assistance. The speed controlled device is of the type in which a frangible bulb 60 containing mercury 61 is caused to rotate through mechanical connection with a moving part, such as an axle of the train. Contacts 62, bridged by the mercury under a very low speed, such as two or four miles an hour, are adapted to be electrically disconnected by the action on the mercury of centrifugal force upon an increase of speed above the figure named. Under the minimum speed referred to, a circuit is established through the brake control magnet 22 as follows: battery 11, conductor 12, conductor 13, conductor 63, contacts 62 and mercury 61, conductor 27, brake magnet 22, conductor 28, and common return conductor 16 back to battery.

Current flowing over the circuit just traced will hold magnet 22 energized, or will reenergize it, if the speed of the train has been lowered to a permissible rate by operation of the automatic brake actuating mechanism. The energized magnet 22 will lift valve 39 to its seat and lift valve 40 from its seat in exhaust port 64 to vent the regulating chamber 49 and cylinder 44 and permit spring 55 to withdraw piston 45 from valve operating position.

A supplemental speed controlled device is shown at 65 similar in construction to the speed controlled device 59, already described. In the speed controlled device 65, however, the contacts are arranged to be disengaged by the mercury only when the vehicle exceeds

5 a predetermined maximum speed at which it is permitted to travel. Under such conditions, magnet 66 in conductor 67 will be deenergized to open the supplemental brake valve 68 and vent the train pipe to apply the brakes. This operation will take place regardless of traffic conditions, so that the vehicle cannot exceed the maximum allowable speed even under safety conditions. In this connection it will be noted that the valve 48 is of such construction as to permit, at such time, air to flow past it to valve 68.

In Figure 2 of the drawing there is illustrated an embodiment of the invention in which provision is made for operating a train under caution conditions as well as under the safety conditions described in connection with Figure 1 and in which a low resistance relay, braking mechanism and speed controlled devices are again made use of.

It will be seen that in this embodiment of the invention coil 69, core 70 and armatures 71 and 72 together form a polarized relay that is responsive to changes in the character of the current flowing in the track rails and to the presence or absence of current in the track rails as well. The changes in the character of the track circuit are preferably produced by changing the polarity of a direct current but such changes may be produced in various other ways, such as by changing the phase or frequency of an alternating current.

When current flows through coil 69 in a certain direction, say from track rail 74 to track rail 73, the soft iron core 70 is given such a polarity that armature 72 is attracted and moved into engagement with contact member 75, while the other armature 71 is not only repelled by the adjacent pole of core 70 but is also urged by gravity out of engagement with contact piece 76 and into engagement with stop 77. When current flows through the coil in the opposite direction, that is from track rail 73 to track rail 74, armature 71 is attracted so that it will move into engagement with contact member 76 and, at the same time, armature 72 will break contact with contact member 75. When no current is flowing through coil 69, both armatures 71 and 72 move out of engagement with their respective contacts.

55 We thus have three conditions of the polarized relay that are made to correspond to the three traffic conditions, i. e., safety, caution, and danger. Under safety traffic conditions, armature 72 is caused to make contact with contact member 75 while armature 71 is moved away from contact 76. Under caution 60 conditions, armature 71 is attracted and moved into contact with contact member 76 while armature 72 is moved out of engagement with contact member 75. Under danger 65 conditions, both armatures will leave their respective contacts.

Under safety conditions, current will flow from track rail 74 and thence through the low resistance coil 69 to track rail 73. Assuming that this will give the core member 69 such a polarity that armature 72 will be attracted to move into engagement with contact 75, a circuit will be established as follows: Battery 77, conductor 78, conductor 79, armature 72, contact 75, conductor 80, coils of relay 81, conductor 82, and common return conductor 83 back to battery.

This will energize relay 81 and lift armatures 84 and 85 thereof into engagement with front contacts 86 and 87 respectively.

The movement of the armature 84 into engagement with the upper contact 86 will close a circuit through the green, or safety, lamp 88, from battery 77, conductor 78, conductor 79, armature 84, contact 86, conductor 89, lamp 88, conductor 90 to common return conductor 83 and back to battery. 80 85

At the same time, armature 85 will close a circuit through brake magnet 91 to hold the brake valve mechanism inoperative, as follows: Battery 77, conductor 78, conductor 79, armature 85, contact 87, conductor 92, conductor 93, conductor 94, brake magnet 91, conductor 95, and common return conductor 83 back to battery.

Under caution conditions, let us assume that current will flow from track rail 73 to track rail 74, instead of from track rail 74 to track rail 73 as was the case under safety conditions. The effect of this is to so energize the low resistance coil 69 as to give to the core member 70 such a polarity that armature 71 will be attracted into engagement with contact member 76 while the other armature 72 will be moved out of engagement with contact member 75.

This will energize relay 96, relay 81, at the same time, becoming deenergized by the opening of the circuit therethrough at contact 75. Current to energize relay 96 will flow as follows: Battery 77, conductor 78, conductor 97, conductor 98, armature 71, contact 76, conductor 99, relay 96, conductor 100, and common return conductor 83 back to battery. This will energize relay 96 and lift armatures 101 and 102 into engagement with the upper contacts 103 and 104, respectively. 110 115

The engagement of contact 103 by armature 101 will close a circuit through caution lamp 105 as follows: Battery 77, conductor 78, conductor 79, armature 84, back contact 106, conductor 107, armature 101, contact 103, conductor 108, yellow, or caution, lamp 105, conductor 90, and common return conductor 83 back to battery. 120

A circuit will also be closed through brake magnet 91 by way of the speed controlled device 109 so that under caution conditions the train must be restricted to a certain predetermined speed in order to prevent an automatic application of the brakes. This cir- 130

cuit may be traced as follows: battery 77, conductor 78, conductor 79, armature 84, back contact 106, conductor 107, armature 102, contact 104, conductor 110, contacts 111, mercury 112, conductor 113, conductor 94, brake magnet 91, conductor 95, and common return conductor 83 back to battery.

Thus, under caution conditions, relay 96 is energized resulting in the lighting of the caution lamp and the energization of brake magnet 91. Should, however, the speed of the train be such as to carry the mercury out of bridging engagement with contacts 111, the circuit through the brake magnet will be broken and the brakes applied. When the speed has been reduced, by action of the brakes, to the permissible speed the circuit through contacts 111 will be restored and the circuit through the brake magnet automatically re-established to release the brakes.

Under danger conditions, let us assume that there is insufficient current available to cause the low resistance relay to attract either armature 71 or 72. The result is that circuits are broken at each of the contacts 75 and 76 so that both relays 81 and 96 are deenergized.

The dropping of the armatures of the relays will establish a circuit through the red, or danger, lamp 114 and bell 115 as follows: battery 77, conductor 78, conductor 79, armature 84, back contact 106, conductor 107, armature 101, back contact 116, conductor 117, lamp 114 and bell 115, conductor 90, and common return conductor 83 back to battery.

It is to be noted that with both relays 81 and 96 deenergized, there is no circuit closed through brake magnet 91 except by way of the speed controlled device 109 and contacts 118 so that the train can be moved only at a very low speed, such as two or four miles per hour. The speed controlled circuit includes battery 77, conductor 78, conductor 97, conductor 98, contacts 118 and mercury 112, conductor 113, conductor 94, brake magnet 91, conductor 95, and common return conductor 83 back to battery. So long as the mercury bridges contacts 118, this circuit will cause magnet 91 to hold the brake valve mechanism inoperative, but a very low speed will be sufficient to break the contact at contact points 118 and set the brakes, as has been stated.

A supplemental speed controlled device is shown at 119 in Figure 2. The contacts 120 in bulb 121 of this controller are arranged to be disengaged by the mercury when the vehicle exceeds the maximum speed at which it is permitted to travel. Under such conditions, magnet 122 in conductor 123 will be de-energized to open supplemental brake valve 124 and vent the train pipe to set the brakes. This operation will take place regardless of traffic conditions so that the vehicle cannot

exceed the maximum speed permitted even under safety conditions.

Brake magnets 122 and 91 may be attached to timing means, as in the embodiment of the invention shown in Figure 1, which would prevent a sudden application of the brakes while the vehicle is passing over a dead section at a switch or cross-over, or this result might be secured by adjustment of the size of the aperture through which the exhaust from the train pipe takes place.

I claim:

1. A train carried system including: train controlling means, electroresponsive means which, when energized, holds the train controlling means inoperative, speed control means for rupturing a circuit through the electroresponsive means when the train is running above a certain intermediate speed, speed control means for rupturing a circuit through said electroresponsive means when a train is running above a minimum speed, means for rupturing the connection through the first speed control means regardless of the speed of the train under certain traffic conditions, means for completing a circuit through said electroresponsive means independently of the two speed control means under certain other traffic conditions, a third speed control means normally completing a circuit through the electroresponsive means but rupturing the same when the train is running above maximum speed independent of the two speed control means.

2. A train carried system including: train controlling means, two electromagnetic devices which, when energized, hold the train controlling means inoperative and the de-energization of either of which renders the train controlling means operative, a circuit normally completed through one of said devices, a speed control means in circuit with said device controlling the maximum speed at which the train can be run under certain traffic conditions, another circuit normally completed through the other of said devices, means acting under certain traffic conditions for including another speed control means in said second circuit, said second speed control means breaking the second circuit at a lower speed than the maximum.

3. A train carried system including: train controlling means, two electromagnetic devices which, when energized, hold the train controlling means inoperative and the de-energization of either of which renders the train controlling means operative, a circuit normally completed through one of said devices, a speed control means in circuit with said device controlling the maximum speed at which the train can be run under certain traffic conditions, another circuit normally completed through the other of said devices, means acting under certain traffic conditions for including another speed control means

in said second circuit, said second speed control means breaking the second circuit at a lower speed than the maximum, and an additional speed control means completing a circuit through said second device to permit the train to run at a minimum speed.

4. A train carried system including: train controlling means, electroresponsive means which, when energized, holds the train controlling means inoperative, a circuit normally completed through said electroresponsive means under safety conditions, means acting under caution conditions for rupturing said circuit and establishing a speed control circuit through the electroresponsive means, said circuit to be automatically ruptured when the train exceeds a certain speed, means for rupturing said second circuit under danger conditions, a circuit including a speed control means through said electroresponsive device to permit the train to proceed at a minimum speed under danger conditions, and a circuit and speed control means controlling the electroresponsive means to establish a maximum speed under safety conditions.

5. A train carried system including: train controlling means, two electromagnetic devices which, when energized, hold said train controlling means inoperative and either one of which, when deenergized, renders the train controlling means operative, a circuit normally completed through one of said devices, a speed control means in circuit with said device controlling the maximum speed at which the train can run under certain conditions, another circuit normally completed through the other of said devices under safety conditions, a second speed controlled means, operating at a certain lower speed than the maximum, and means acting under caution conditions to rupture said second circuit and establish a circuit to include said second speed control means.

45 6. A train carried system including: train controlling means, two electromagnetic devices which, when energized, hold said train controlling means inoperative and either one of which, when deenergized, renders the train controlling means operative, a circuit normally completed through one of said devices, a speed control means in circuit with said device controlling the maximum speed at which the train can run under certain conditions, another circuit normally completed through the other of said devices under safety conditions, a second speed controlled means operating at a certain lower speed than the maximum, means acting under caution conditions to rupture said second circuit and establish a circuit to include said second speed control means, means for rupturing said second circuit including the second speed control means under danger conditions, and a circuit including a speed control

means established through said second device permitting the train to proceed at a minimum speed under danger conditions.

Signed at New York, in the county of New York and State of New York, this 18th day ⁷⁰ of September 1917.
